UNITED STATES PATENT OFFICE

AARON S. NICHOLS, OF CHICAGO, ILLINOIS.

BOX.

SPECIFICATION forming part of Letters Patent No. 367,836, dated August 9, 1887.

Application filed April 20, 1887. Serial No. 235,557. (No model.)

To all whom it may concern:

Be it known that I, AARON S. NICHOLS, a citizen of the United States, residing at Chicago, in the county of Cook and State of Illinois, have invented a new and useful Improvement in Boxes, of which the following is a specification.

This invention relates to small-sized boxes primarily designed to be used as pocket match-boxes, but equally adapted to hold other slender similarly-shaped articles, and also adapted to be used as coin-holders and as receptacles for other articles.

The invention consists of two inclosing end caps rigidly secured together by an interior connection and a body inclosed in said ends and capable of being longitudinally moved therein, the body being provided with an opening, which in one position of the body is concealed or covered by one of said end caps and in the other position is exposed.

The invention also consists in such a box as above described when provided with an inclined partition, whereby it is specially adapted to use with matches and similar articles.

In the accompanying drawings, which form a part of this specification, and in which similar letters of reference indicate like parts, Figure 1 is a side elevation of a rectangular-shaped box adapted to be carried in the pocket and embodying my invention. Figs. 2 and 3 are longitudinal edge views of the same, showing the movable body in different positions. Fig. 4 is a section on line 4-4 of Fig. 2. Fig. 5 shows the blank by which the inclosing end caps may be connected together, and which at the same time forms the inclined partition used in the box when employed for matches. Fig. 6 shows this blank bent into shape in perspective. Fig. 7 shows a suitable way of joining the end caps when the inclined floor is not desired. Fig. 8 is a section, similar to Fig. 4, of the modification shown in Fig. 7.

In the drawings, A B are the inclosing end caps, struck out of sheet metal and provided with rims *a* of a width greater than the length of movement desired for the body.

C is the movable body, also formed of sheet metal and conforming to the interior of the cap-rims closely, so that there may be sufficient friction between it and the rims to pre-

vent the body from accidental sliding. The body has a slight longitudinal movement within the rims of the caps, and is provided with an opening near one end, as shown at *c*, 55 through which the contents of the box are inserted or withdrawn. The longitudinal movement is just sufficient to cover and uncover this opening. Figs. 1, 2, and 4 show this opening uncovered, and at Fig. 3 the body is shown 60 as moved to its other position, whereby the opening *c* is concealed by the rim of the cap B.

Extending through the interior of the body, and rigidly connecting the two caps together, is a connecting-piece, E, which may be one or 65 more simple wires or strips, as shown in Figs. 7 and 8, or the blank shown in Figs. 5 and 6. The strips, where such are used, are securely soldered at *d* to the inside surface of the caps, so the latter cannot rock thereon. The blank 7c is, however, very desirable for this interior connection, as it may be bent to the shape shown in Fig. 6, giving it two broad end flanges, *e*, well adapted to be soldered to the caps, and an inclined dividing floor or partition, F, 75 which, in addition to the function hereinafter ascribed to it, also acts to prevent the collapse of the body. The portions *f* of the blank lie flat against the sides of the body. The lower end of the inclined floor F is located just below 80 the opening *c* when the latter is in the open position, and the matches or other articles contained in the box are thus caused to slide down said floor and automatically present themselves at the opening for withdrawal.

It will be understood from what has already been said that the boxes are opened and closed by the longitudinal movement of the body within the rims of the caps. I of course do not wish to be limited, where the inclined floor F 90 is used, to the particular blank E, nor to the use of wires where such floor is not used, as it is obvious that many changes from both these constructions may be employed. Nor do I wish to be limited in the matter of the size or 95 form of the box, in both of which respects the construction may be greatly varied to adapt the box to different uses.

I claim—

1. The box consisting of the inclosing end 100 caps rigidly secured together and the movable body having an opening near one end for the

insertion or withdrawal of the contents, substantially as specified.

2. The box consisting of the inclosing caps secured together and a movable body, in combination with the inclined floor F, substantially as specified.

3. The combination, with the caps and the

movable body, of the blank E, uniting the caps and forming the inclined floor, substantially as specified.

AARON S. NICHOLS.
